UNITED STATES PATENT OFFICE.

ALONZO E. RHOADES, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

THREAD-POSITIONER.

1,261,620.

Specification of Letters Patent. Patented Apr. 2, 1918.

Application filed September 13, 1916. Serial No. 119,953.

To all whom it may concern:

Be it known that I, ALONZO E. RHOADES, a citizen of the United States, residing at Hopedale, county of Worcester, and State of Massachusetts, have invented an Improvement in Thread-Positioners, of which the following description, in connection with the accompanying drawings, is a specification, like characters on the drawings representing like parts.

The present invention relates to filling replenishing looms, and more particularly to the means for positioning the filling for the action of the filling parter. In looms of the feeler type, wherein a fresh supply of filling is furnished prior to complete exhaustion of the filling, it is customary to provide means to part or sever the filling leading from the filling carrier to be abandoned close to the shuttle, and then carry the end of the filling leading from the cloth selvage into position to be severed later by the temple thread cutter. In practice it has been found convenient to mount the parting means, which parts the filling adjacent the shuttle, on the shuttle-feeler or to otherwise arrange it that the parting means may be normally maintained in inoperative position and be moved to operative position only on call for filling replenishment.

Since the filling leading from the filling carrier to be abandoned extends from the cloth selvage to the shuttle-eye at the time the filling parter is moved to operative position, it frequently happens that the filling is not in proper position to be engaged by the parter. Sometimes it may be too high and sometimes too low to properly enter between the jaws of the parter. This may be occasioned by slack filling between the cloth selvage and shuttle or by the lay movement or both. In any event, if the parter is to perform its function it is essential that the filling be properly positioned for engagement by the parter. If the filling is too high for the action of the parter when the parter moves to operative position on call for filling replenishment, it should be lowered, and if too low it should be raised. Failure of the parter to act, usually results in the piece of filling leading from the cloth selvage to the shuttle, being carried into the

shed on a pick of the shuttle after replenishment thereby producing defective cloth. 55

An important feature of the present invention, therefore, consists in filling positioning members, one above and the other below the path of the shuttle during weaving, which on call for replenishment correct 60 the position of the filling and insure its engagement by the parting means. This feature of the invention, as one convenient practical form thereof, may be carried into effect by causing the said members to move 65 toward each other or in a direction of approach, so that if the filling is too high for the action of the parter, it will be lowered to proper position, or if too low it will be raised to such position. 70

Simplicity of structure and operation dictates that the filling positioning means be so devised and constructed that it shall not interfere with the action of the parter itself which, when it moves to operative 75 position for performing its parting function, should find the filling already positioned for its action. Another important feature of the invention, therefore, consists in the association and combination of the 80 positioning members and their operating connections so that on call for filling replenishment, soon after the shuttle has reached the replenishing shuttle-box, the positioning members shall move to position 85 the filling for the action of the parting means. This feature of the invention may be variously carried into effect, but in the form of the invention illustrated, the positioning members are mounted at the rear of 90 the lay and project frontwardly across the raceway and are caused to be moved in the discharge of their positioning function when the feeler means or change shaft which is operatively connected therewith is moved 95 responsive to a call for replenishment.

Various other features of the invention will be hereinafter described in addition to those noted and in connection with the accompanying drawings, which illustrate one 100 good practical form of the invention, and the invention in its true scope, will then be defined by the claims.

In the drawings:—

Figure 1 is a top or plan view of a portion of the loom elements, showing the fill-

ing parting means in operative position and the relation of the parting means and filling positioning means.

Fig. 2 is an enlarged side elevation, showing the filling positioning means and its operative relation to the associated parts, some portions of the breast beam and lay being broken away, and the two members of the positioning means being shown in the relation assumed by them upon call for filling replenishment.

Fig. 3 is a view similar to that of Fig. 2, showing the normal position of the positioning members during weaving when the loom is running regularly.

Fig. 4 is a detail in perspective, showing certain features of the positioning means and their connections.

The loom frame and weaving instruments connected thereto may be of any useful character, as may likewise be the filling parter which acts upon the filling after a call for replenishment to part or cut it near the shuttle when the latter is in the replenishing shuttle-box. It is now quite common to part the filling near the shuttle, clamp the end leading from the cloth selvage, and then move the parter and clamp forward to position the filling for the action of a temple thread cutter. The particulars and details of filling parter construction or the combined parter and clamp form no essential feature of the present invention, which has to do more especially with the means for positioning the filling, extending between the cloth selvage and shuttle, for the action of a filling parter regardless of its detail construction.

In order, however, to make clear the present invention, and the relation thereof with the associated parts, Fig. 1 of the drawings shows the lay 1, having the usual shuttle-box 2, only one being partially indicated, the cloth 3, the temple 4 which may be provided with a temple thread cutter 5, the shuttle 6 in the box at the replenishing side of the loom and a filling parter 7 having the usual parting jaws 8 and 9, and a thread clamp 10. As above noted these parts may all be of usual construction, and as shown are or may be similar to the corresponding parts in the patent to A. W. Clement, No. 641,763, dated Jan. 23, 1900, wherein, upon call for replenishment the parter and clamp are moved from a front or inoperative position toward the lay into an operative position to part and clamp the filling. It is usual to associate the parter or the parter and clamp with the usual shuttle-feeler, and if desired this may be done with the parter employed with the present invention.

The invention contemplates positioning the filling between the cloth selvage and shuttle, so that it may be engaged and parted by the filling parting means. If the fill-

ing be too high the positioning means will lower it, and if too low it will raise it upon call for replenishment, so that when the parter is moved to operative position it will find the filling held in correct location ready for its action. To this end the positioning means comprises two members normally held, the one at one side and the other at the other side of the path of the shuttle, so that during weaving the filling will be laid between the two members, and should a call for replenishment occur, the two members will move toward the position which the parter will occupy when it moves into operative position, and so locate the filling, whether it be too high or too low, that the parter will unerringly engage and part it.

In the present instance of the invention, the members of the positioning means comprise fingers 11 and 12 which extend from the rear of the lay across the raceway, as indicated in Fig. 3, so that the shuttle, as it is picked to the replenishing side of the loom during weaving may lay the filling between the two members 11 and 12. As a convenient practical way of supporting and operating the two positioning members, there is secured to the rear of the lay 1, a bracket 13, having a rearwardly projecting arm 14 provided with supporting lugs or pins 15 and 16 to which the upper and lower positioning members may be connected. In the illustrated form of the invention the members 11 and 12 are formed as sprung fingers, one end of each of which is coiled about its supporting stud or pin and secured, so that the normal tendency of the fingers is to approach each other into the position indicated in Figs. 2 and 4, when permitted to do so. Obviously this arrangement, while simple, light and efficient, may be changed within the expected skill of one familiar with the art.

Rising from the bracket 13 is a guide 17 provided with a slot 18 through which the upper and lower members 11 and 12 may extend. This guide is not always necessary, but in some cases it affords a convenient and simple means for guiding the members 11 and 12 in their relative movements. If desired a pad 19 of leather or other non-metallic substance may be employed upon one side of the guide 17, and when used will be provided with the guiding slots 20 and 21, preferably separated by an unslotted portion 22 to limit the closing movement of the members 11 and 12. Since this pad may be readily changed, the relation of the members 11 and 12 when in closed relation may obviously be made to suit conditions of use.

Mounted for rocking movement between the members 11 and 12 is a separator for normally holding the members in separated relation, as indicated in Fig. 3. Obviously instead of having the members normally spring pressed toward each other and held

apart by a separator, the reverse arrangement may be employed and is of course an equivalent.

The separator, in the present instance of 5 the invention, is preferably formed as a cam 23 connected to a shaft or stud 24 mounted for rocking movement on the extension 14 of the bracket 13, and is located between the positioning members 11 and 12, the construction 10 being such that when the separator or cam 23 is turned into the position Fig. 3, the members 11 and 12 will be separated, and they will be held separated for the passage 15 of a shuttle between them until the separator or cam 23 is turned into the position indicated by Figs. 2 and 4, whereupon the members 11 and 12 will move toward each other to either raise or lower the filling laid between them by the shuttle, and position 20 it for the action of the parter.

The present invention in its preferred form contemplates, that the filling be positioned for the action of the parter upon call for replenishment, so that when the parter 25 reaches operative position it will find the filling in proper location. In the present instance the separator or cam 23 is operatively connected to the change or transverse shaft, which upon indication of substantial 30 exhaustion of the filling is rocked in a manner and by the feeler means well understood by those skilled in the art. To this end the shaft 24 of the separator in the present instance of the invention has secured thereto a 35 crank arm 25, which is joined at 26 to an arm 27 pivoted at 28 to a controller or arm 29. The arm 29 is pivoted at 30 to a bracket 31 secured to the lay 1, and is provided with a stop 32, which under the weight of the 40 parts or in response to a spring, such as 33, or both, normally rests upon the top edge portion of the bracket 31, the construction being such that when the stop 32 is resting upon the bracket 31, as in Fig. 3, the actuator 45 29 is in lowered position and the separator or cam 23 is held, as in Fig. 3, with the positioning members 11 and 12 in normal separated relation.

The breast beam 34, Fig. 2, has secured 50 thereto suitable supports, as 35 of usual and well known construction, for the change or transverse shaft 36. Secured to the change or transverse shaft 36 is an arm 37 provided with a lug or pin 38, above which the arm 55 or actuator 29 moves back and forth with the lay during normal weaving operations, as indicated in Fig. 3; the actuator or arm 29 at such times being in lowered or normal position. Upon call for replenishment of 60 filling, the change or transverse shaft 36 is rocked contra-clockwise in Fig. 2, as usual and as well known, thereupon lifting the arm 37 and causing the lug or pin 38 to raise the actuator or arm 29, and through 65 the link 27 turn the separator or cam 23 to

70 permit the members 11 and 12 to move from their open or normal position, Fig. 3, to their more nearly closed relation, Figs. 2 and 4 to thereby locate the filling for the action of the parter.

After the filling has been replenished, and as the change shaft returns to initial position, the arm 37 is lowered again into its normal position, and the separator or cam 23 is again turned to cause the members 11 and 12 to assume their separated relation and the stop 32 to rest upon the arm or bracket 31, substantially as indicated by Fig. 3.

Obviously other forms of connections and mechanical details will suggest themselves, 80 as a means for controlling the positioning members 11 and 12 so as to present the filling for the action of the parter, but the form of the invention described has been found practical and simple, and while the spring 85 action of the members is a convenient form of construction, they may be otherwise controlled.

In order that the lower member 12 may 90 extend across the path of the shuttle or cross the raceway without interfering with the shuttle, the lay may be provided with a groove 39 into which the lower positioning member may extend below the shuttle path while the upper positioning member may 95 project frontwardly above said path.

Claims:

1. In a filling replenishing loom, the combination of the lay and shuttle-boxes, means 100 for parting the old or spent filling between the cloth selvage and shuttle-box, filling positioning members normally maintained one above and the other below the path of the shuttle, that the shuttle and filling leading therefrom may pass between them during weaving, and means rendered effective upon call for replenishment to move said members toward each other to position the filling for the action of the parting means.

2. In a filling replenishing loom, the combination of the lay and shuttle-boxes, means for parting the filling, filling positioning means carried by the lay and comprising two members located at opposite sides of the path of the shuttle that the shuttle and filling leading therefrom may pass between them during weaving, and means for causing said members to lift the filling if too low or lower it if too high for the action of the parting means.

3. In a filling replenishing loom, the combination of the lay and shuttle-boxes, means for parting the filling, filling positioning members projecting from the rear of the lay transversely of the raceway above and below the path of the shuttle, and means operative upon call for filling replenishment to raise one member and lower the other to position the filling for the action of the parting means.

4. In a filling replenishing loom, the combination of the lay and shuttle-boxes, means for parting the filling, filling positioning members carried by and projecting from the rear of the lay transversely of the raceway above and below the path of the shuttle, and means operative upon call for filling replenishment to raise one member and lower the other to position the filling for the action of the parting means.

5. In a filling replenishing loom, the combination of the lay and shuttle-boxes, means for parting the filling, filling positioning means carried by the lay and comprising two members located respectively at opposite sides of the path of the shuttle that the shuttle and filling leading therefrom may pass between them during weaving, and means for causing said members to move toward each other on call for replenishment to position the filling for the action of the parting means.

6. In a filling replenishing loom, the combination of the lay and shuttle-boxes, parting means for the filling, filling positioning means comprising two members normally located respectively one above and the other below the raceway, a change shaft, and means effective when the change shaft is rocked for moving said two members toward each other.

7. In a filling replenishing loom, the combination of the lay and shuttle-boxes, parting means for the filling between the cloth and a shuttle-box, filling positioning means comprising two fingers carried by and projecting from the rear of the lay, means normally acting to hold said fingers in separated relation, and means effective on call for replenishment for causing said fingers to move in the direction of approach to position the filling.

8. In a filling replenishing loom, the combination of the lay and shuttle-boxes, filling parting means, filling positioning means comprising spring actuated members mounted on the lay and normally held in separated relation, and means effective on call for filling replenishment to permit said members to be moved yielding toward each other to position the filling.

9. In a filling replenishing loom, the combination of the lay and shuttle-boxes, filling parting means, filling positioning means

comprising spring actuated members mounted on the lay and normally held in separated relation, guiding means for said members, and means effective on call for filling replenishment to permit said members to be moved yielding toward each other to position the filling.

10. In a filling replenishing loom, the combination of the lay, filling parting means, filling positioning members, carried by the lay and extending across the raceway from the rear of the lay, holding means acting to hold said members in separated relation during weaving, a change shaft, and means effective on rocking movement of the change shaft to render said holding means ineffective and permit the positioning members to close upon the filling.

11. In a filling replenishing loom, the combination of the lay, filling parting means, filling positioning members carried by the lay and extending across the raceway from the rear of the lay, holding means acting to hold said members in separated relation during weaving, a change shaft, and means effective on rocking movement of the change shaft to render said holding means ineffective and permit the positioning members to close upon the filling and a stop for limiting the movement of said members.

12. In a filling replenishing loom, the combination of the lay and shuttle-boxes, a bracket projecting from the rear of the lay, an upper and a lower filling positioning member mounted on the bracket, and means rendered effective on call for replenishment for moving said members toward each other.

13. Filling positioning means, comprising, in combination an upper and lower member carried by the lay, a separator normally acting to hold said members in separated relation transversely of the shuttle path, that the shuttle and filling may pass between them during weaving, means for turning the separator on call for filling replenishment to effect movement of said members toward each other, to position the filling, and parting means for parting the filling.

In testimony whereof, I have signed my name to this specification.

ALONZO E. RHOADES.
